UNITED STATES PATENT OFFICE

2,630,757

COMBINED TYPE SERIES PUMP FOR
FLASHABLE LIQUIDS

Lionel R. Cartier, O'Fallon, Ill.; Effie Mae Cartier and Norman J. Gundlach, executors of said Lionel R. Cartier, deceased, assignors to Independent Engineering Company, Inc., O'Fallon, Ill., a corporation of Illinois

Application March 26, 1948, Serial No. 17,282

7 Claims. (Cl. 103—5)

1

The present invention relates to a pump for flashable liquids. For example, the pump of this invention is especially valuable in connection with the pumping of liquid oxygen that has a very low boiling point, resulting in a problem of vapor locking in the pump due to evaporation of the liquid oxygen to vapor within the pumping chambers. Such vapor locking restricts or prevents the pump from drawing in a full charge of liquid to be pumped.

It is an object of the invention to provide a pump that will not cause flashing of the liquid, without requiring the use of pressure above the liquid in the liquid supply tank.

It is a broad object of this invention to provide a pump that will prevent sudden vaporization, or indeed any substantial degree of vaporization, of a highly volatile liquid being pumped, especially where such vaporization results from the increase in temperature on the suction stroke of the pump in the liquid drawn into the pumping chamber, sometimes coupled with a reduction in flash point of the liquid resulting from any substantial reduction in pressure on the liquid entering the pumping chamber.

A specific object of the invention is to provide a pump having an intake loading means that will maintain a pressure on the liquid being taken into the pump to assure substantially full liquid charge to the pump, even if some liquid in the pumping chamber evaporates as a result, for example, of heat generated on the preceding compression stroke.

A more specific object of the invention is to provide a pump of the piston or plunger type, having a loading means that causes the intake chamber to be loaded under a certain pressure that will prevent obstruction of intake because of vaporization of the liquid. More particularly, it is an object of the invention to provide a pump of the foregoing kind having a loading chamber that entraps a charge of liquid but does not substantially increase its temperature; and which loading chamber is so interrelated with the pump that it positively discharges the entrapped amount of liquid into the intake chamber of the pump during the suction stroke.

A further object of the invention is to attain the foregoing charging of the intake chamber of the pump by a loading means without increasing the temperature of the liquid, and to interrelate the operation of the loading means, so that the loading chamber may be charged with liquid during the compression stroke of the pump, and may eject the charge of liquid, by application

2

of pressure, into the intake chamber during the suction stroke.

A particular object of the invention is to provide, in connection with a plunger type of pump, a loading chamber that obtains a charge of liquid by moving against the liquid, and without substantial increase of temperature during the charging process.

Other objects of the invention will appear in the description to follow.

In the drawings:

Fig. 1 is an elevation of the pump; and

Fig. 2 and Fig. 3 are, respectively, upper and lower diametrical sections of the pump.

The pump comprises a main cylinder 10 that has a bore from end to end providing various cylindrical chambers, as will appear. (The term "cylinder" used herein is not specifically limited to circular shapes, although for conventionally-known reasons, pump cylinders are usually circular in cross section.) The lower end of the pump cylinder is of reduced diameter to provide a pump or displacement chamber 12, wherein a piston or plunger reciprocates as will appear. At the upper end of the displacement chamber 12, the bore flares outwardly at 13 to provide a seat for a tapered packing seat element. This flaring portion 13 terminates in a somewhat wider cylindrical portion 14 to receive packing. Above the packing portion 14, the bore widens out to a diameter 15 that may continue evenly to the top of the main pump cylinder 10.

A plunger or displacement member, here in the form of a piston 18, is attached to a piston rod 19, and is disposed within the displacement chamber 12. The piston rod has a reduced extension that is threaded as at 20, and over this reduced extension the piston may be built up by a plurality of rings formed by alternate brass and leather washers or carbon rings clamped into place by a nut 21. It is preferred to use the illustrated structure of the piston 18 with the packing rings, rather than a plunger with clearance in the displacement chamber, as is known in the art.

Within the flaring portion 13 above the displacement chamber 12, a tapered packing seat element 23, made of brass or the like, is inserted in a manner to interfit with the flare 13. The upper edge of the packing seat 23 may be sharpened to a somewhat dulled edge. Packing 24, preferably of the chevron leather type, is then applied above the packing seat 23, and within the packing area of the pump cylinder bore.

A packing gland 25 is applied above this packing. This packing gland is shaped to receive a generally tubular packing gland extension 26 that is preferably rabbeted to fit over a projecting end on the primary packing gland 25. As indicated, the packing gland extension 26 is supplied with a plurality of radial ports 27, for a purpose to appear.

The upper end of the tubular packing gland extension 26 receives an upper piston rod adjusting gland 30, rabbeted for an interfit as indicated. This upper adjusting gland is flanged outwardly at 31 above the top of the pump cylinder 10, and may have a relatively loose fit within the upper bore 15 of the pump cylinder. As indicated, the piston rod 19 passes through the foregoing elements, and above the top of the upper adjusting gland 30.

The outside surface of the upper part of the pump cylinder 10 receives, on opposite sides, two tubular rod guides 33 that may be slightly flattened at their contact surfaces against the pump cylinder 10. They are secured to the pump cylinder, it having been found that silver solder along the extended interfaces is sufficient for the purpose. These two rod guide tubes project above the top of the pump cylinder 10, and pass through the flange 31 of the upper adjusting gland 30, which may slide on the tubes. Above the flange 31, the two tubes are threaded to receive packing ring adjusting caps 38 that may be turned, they being hexagonal in external shape, to force the flange 31 and the several elements of the packing extension down to compress the packing 24 properly against the piston rod 19 to prevent leakage.

The piston rod adjusting gland 30 has a recess 37 in its upper surface. This recess is adapted to receive packing 38 fastened firmly into position by a packing gland 39, that is attached by screws 40 to the upper surface of the upper gland 30. This affords a packing gland at the top of the piston rod.

The piston rod 19, at its upper end, is reduced and threaded, as shown at 42. A crosshead type of adapter 43 is threaded over the threaded extension 42, and above this the piston rod is threaded into a drive member 44, by means of which the piston may be attached to a suitable source of power for its reciprocation. The drive member 44 is inset into a recess in the crosshead 43, and these parts may be welded together, as indicated at 45.

The pump cylinder 10, within the upper part 15 of its bore, has a plurality of ports 46 through its wall. Adjacent its top, it has tapped openings 47 that can receive screws for attaching the pump to a support.

There is an expandable and contractible loading chamber forming loading means connected with the displacement chamber 12. It here is illustrated in the form of a fixed piston member and a movable cylinder telescoped over the fixed piston, but it will be understood that this choice of arrangement is not essential. As illustrated, the bottom end of the displacement chamber 12 in the pump cylinder 10 is enlarged to provide an internally threaded portion that receives a tubular extension 50, this element being threaded at its upper end for interengagement with the aforesaid bottom end of the pump cylinder 10. A hexagonal flange 51 enables the two parts to be joined. This tubular extension 50 has its outer end designed to act as the fixed plunger, over which a liquid loader cylinder 52 is fitted to re-

ciprocate. The liquid loader cylinder 52 is flanged at 53. A pair of connecting rods 54 have their lower ends threaded into the flange 53 and locked by lock nuts 56. The rods 54 pass upwardly through guide tubes 57 that are attached to the outside wall of the pump cylinder 10 similarly to the attachment of the upper guide tubes 33. The rods 54 continue upwardly through the guide tubes 33, and pass through the crosshead 43, to which they are attached by suitable nuts 58 and 59. The lower threaded connection of these guide rods 54 into the liquid loader cylinder 52 provides for an adjustment of the rods. Also, adjustment may be made at the top in the manner obvious from the drawings.

The movable loader cylinder 52 has intake ports 60 through its bottom wall. It also provides a guide for a loader valve stem 61, at the top of which is formed a loader valve or check valve 62 of the tappet type. This valve engages against a valve seat 63 on the inner surface of the loader cylinder 52. A suitable pin 64 secures the valve for limited motion within the interior of the movable cylinder 52.

The expandable loading chamber is connected with the displacement chamber 12. In the preferred form here illustrated, the element 50, that constitutes the fixed piston, has a bore extending from end to end, so as to provide a passage between the loading and displacement chambers. The upper end of this bore is drilled down to a valve seat 66 that may receive a ball check valve 67. This valve is enclosed into the upper part of the passage by a tubular nut 68, the lower end of which will prevent escape of the ball 67 but is notched so as not to obstruct the flow of liquid past the ball when it is in its upper position.

Below the valve seat 66, the inner bore of the element 50 is reduced as at 69, and terminates in a lower enlargement, the shoulder being notched at 70 to prevent a seal-off by a ball check valve 71. This ball valve is retained by a fitting 72 that is tubular and provides a suitable upper edge against which the ball valve 71 may seat. Obviously, types of check valves other than ball check valves may be used. The fitting 72 is threaded into the lower end of the fixed piston element 50. It is evident that the tubular element 50, connecting the loading chamber with the displacement chamber 12, provides an outlet from the loading chamber and an inlet to the displacement chamber.

The displacement chamber 12 has an outlet 75 to which a short tube 76 is attached. This tube enters an elbow 77 that, in turn, receives a fitting 78. The upper end of the elbow 77 affords a shoulder providing a valve seat 80 to receive a ball check valve 81 that is confined within a chamber 82 in the fitting 78. The upper end of this chamber is notched at 83. A reduced portion 84 continues the opening through the fitting 78 and affords an upper valve seat 85 to receive an upper ball valve or check valve 86. This upper ball valve is confined by a fitting 87 threaded into the fitting 78 and notched at 88 to prevent obstruction of flow when the valve ball 86 rises against it. An outlet tube 90 can lead off the liquid being pumped.

Operation

The pump is immersed in the source of liquid and there secured. The present description will be related to liquid oxygen, which has a boiling point of -183°C. , as the element demonstrates

the problems that are solved by this pump, because of its great likelihood of flashing into vapor during the pumping operation. In a typical installation, the pump will be supported so that the top of the liquid oxygen supply tank comes approximately to the bottom of the guide tubes 33. If the liquid tank is within an outer shell, then the pump may be given support by screws that enter holes 47 that are provided adjacent the top of the pump cylinder 10 on opposite sides thereof. The drive member 44 is attached to a suitable source of power so that it may be reciprocated.

The drawings show the piston or plunger 18 in its upper position, that is to say, at the upper end of its stroke. In this position, the moving loader cylinder 52 is also in its upper position. It will be assumed that the displacement chamber 12 is charged with liquid oxygen.

When the piston descends, the liquid oxygen within the chamber 12 is prevented from return egress through the fixed piston 50 because of the ball valve 67 that seats on the seat 66, and the additional ball valve 71 that seats in the fitting 12. Consequently, liquid in the chamber 12 is ejected under pressure through the outlet 75. It then passes the ball valve 80 and the ball valve 86. These last two valves 81 and 86 check the return flow of the liquid so that it is caused to pass into the outlet pipe 90.

In the downward movement or pressure stroke of the piston 18, which is attached to the cross-head member 43, the rods 54 are likewise caused to descend. These rods are attached to the moving cylinder 52, which therefore descends during the downstroke of the piston. In the down or charging stroke of the cylinder 52, the valve 62 will be caused to lift from the seat 63, so that an additional charge of liquid oxygen flows inwardly without substantial increase in temperature through the ports 60 to enter the moving cylinder 52. A factor involved in this action is the movement of the moving cylinder 52 against the liquid, so that the inertia factor adds to the charging pressures instead of subtracting from them. This action is more like an entrapment of liquid than it is like the sucking of liquid produced by the suction stroke of the piston. As a result, there is no substantial opportunity for the oxygen to flash into vapor as a result of serious temperature increase or pressure drop.

When the piston 18 reaches the bottom of its stroke, the moving cylinder 52 will likewise be at the bottom of its stroke, and a new charge of liquid will be entrapped within the moving cylinder 52. Incidentally, the check valve 71 prevents the descent of the moving cylinder 52 from drawing liquid downwardly. When the moving cylinder 52 is at the bottom of its stroke, the valve 63 again closes, and will be maintained closed thereafter during the upstroke, by action of the entrapped liquid against it.

Thereafter, the piston 18 will be caused to ascend again on a suction stroke, and also the moving cylinder 52 will be caused to ascend at the same time on its discharging stroke. The normal suction action of the piston 18 in the present pump becomes more of a withdrawal action that permits liquid, previously entrapped by the moving cylinder 52, to enter the displacement chamber 12. The ascent of the moving cylinder 52 along the fixed piston 50 causes the liquid entrapped by the valve 62 within the moving cylinder 52 to be moved upwardly, without reduction of pressure or rise of temperature to any sub-

stantial degree, past the check valves 71 and 67 to charge the piston chamber 12. The two check valves prevent return flow of the liquid from the chamber.

With this arrangement, the liquid is initially entrapped within the cylinder 52 without substantial rise in temperature or reduction in pressure to cause it to flash therein. Then it is positively discharged into the pumping chamber 12, so that, even if there is sufficient heat in the pumping chamber 12 from the previous compression stroke, and consequent flashing of some liquid into vapor, the charging force will nevertheless cause full charging of the pumping chamber with liquid. It may be observed that the diameter of the fixed plunger 50 is greater than that of the movable piston 18. Hence the cylinder 52 can assuredly fill the displacement chamber 12 of the pump. The low pressures in the operation of the loading cylinder 52 may limit the amount of liquid taken into it on each loading operation, but its size is great enough yet to assure filling of the displacement chamber 12 with enough pressure to avoid or overcome the effects of flashing therein. Preferably, as shown, no sealing is used between the cup 52 and the piston 50, as this makes the arrangement more flexible, and may provide an avenue of leakage for any excess of liquid in the cylinder 52 over the capacity of the displacement chamber.

Liquid is restrained from passing upwardly by the piston rod because of the packing 24. Such liquid as may escape around the packing 24 to within the packing gland extension 26 can readily escape through the ports 27 and 46, as either a liquid or a gas, depending upon temperature and pressure conditions. The escape of liquid through the top of the pump is prevented by the presence of the packing 37.

As already noted, the positional relationship of the cylinder 52 to the piston 18 is adjustable by means of the lower connection of the connecting rods 54 to the flange 53 of the moving cylinder 52, or by means of the upper connection 45 including the nuts 57 and 58 that attach the rods 54 to the crosshead member 43.

The principal packing 24 may be tightened by turning down the packing nuts 36 that, as previously noted, have hexagonal exteriors, as shown in Fig. 1. For example, turning these cap nuts 36 down will force the flange 31 of the topmost gland member 30 down. Such movement is transmitted through the extension 26 to the gland member 25 and thence to the packing 24.

Furthermore, the upper packing gland 37 may be adjusted by turning the screws 40 down to tighten the same.

It is fairly evident that the pump can be readily disassembled for repair or replacement of any of its parts. And, if it is to be used in a place where it is not necessary to maintain the temperature conditions, the moving cylinder 52 may be disconnected, and thereafter the pump used in conventional manner.

65 What is claimed is:

1. In a pump for flashable liquids, a displacement chamber, an outlet therefrom, a displacement member movable inwardly and outwardly of the displacement chamber on pressure and suction strokes, respectively, a movable loading cylinder, a plunger fixedly connected with the displacement chamber, the loading cylinder being mounted telescopically over the loading plunger and movable over the same, to vary the internal capacity of the loading cylinder, passage

means connecting the interior of the loading cylinder and the displacement chamber, check valve means in the passage means admitting flow from the cylinder to the displacement chamber, check valved passage means into the loading cylinder to admit liquid to the loading cylinder when it moves in a capacity-enlarging direction, and means connecting the loading cylinder and displacement member for movement of the loading cylinder in a capacity-enlarging direction when the displacement member is moving on its pressure stroke, and for movement of the loading cylinder in a capacity-reducing direction when the displacement member is moving on its suction stroke.

2. The pump of claim 1, wherein the passage means connecting the loading cylinder and the displacement chamber is disposed through the fixed plunger.

3. The pump of claim 1, wherein the means connecting the loading cylinder and displacement member comprises means to apply movement to the displacement member, and rod means connecting the movement applying means and the movable cylinder, and means to adjust the effective length of the rod means to vary the distance between the movement applying means and the cylinder and hence to vary the position of the movable cylinder with respect to its fixed plunger for any position of the displacement member.

4. In a pump for flammable liquid: a displacement chamber, a displacement member operable therein on a suction stroke and a pressure stroke, an outlet from the chamber, loading means in the form of relatively movable, telescopic cylinder and plunger members, providing an expansible loading chamber, inlet check valve means opening through one of said members to admit flow into the loading chamber, means interconnecting the loading means and the displacement member, to expand the loading chamber on the pressure stroke of the displacement member and to contract the loading chamber on the suction stroke of the displacement member, said loading chamber being expansible to collect a charge of liquid to be pumped, check-valved passage means connecting the loading chamber and the displacement chamber, the contraction of the loading chamber operating to force the collected charge through the passage means into the displacement chamber, the inlet check valve means of the loading means chamber including a freely movable tappet valve, opened by the liquid during the expanding movement of the loading chamber, and closed by the collected liquid during the contracting movement of the loading chamber.

5. In a pumping apparatus, a displacement chamber and a displacement member movable

in the chamber on pressure and suction strokes to decrease and increase respectively the volume of the chamber, an inlet into the chamber, an outlet from the chamber, an inflow valve means in the inlet, operable to admit inflow therethrough into the chamber but prevent outflow therethrough from the chamber, and means to load the chamber upon the suction stroke of the displacement member, including a loading cylinder member and a loading plunger member, one of which loading members is fixedly attached to the displacement chamber and the other of which is movable, the loading members being interfitted so that the relative movement between the loading plunger member and the loading cylinder member in one direction expands the fluid capacity of the loading cylinder member, and relative movement in the other direction contracts said fluid capacity, the inlet of the displacement chamber being connected into the loading cylinder, and being an outlet from the loading cylinder, an inlet to the loading cylinder having an inflow valve therein operable to admit inflow but prevent outflow through the said inlet, the effective displacement of the loading cylinder being at least as great as that of the displacement chamber, and means interconnecting the movable loading member and the displacement member for movement of the movable loading member in a direction to increase the loading cylinder capacity when the displacement member moves on its pressure stroke, and to decrease said capacity when the displacement member moves on its suction stroke.

6. The combination of claim 5 in which the effective displacement of the loading cylinder is greater than that of the displacement chamber.

7. The combination of claim 5, and outflow valve means in the outlet of the displacement chamber operable to admit outflow but prevent inflow through the outlet.
